[57] CLAIM

The ornamental design for a ceiling fan simulating an aircraft engine, as shown and described.

DESCRIPTION

FIG. 1 is a bottom plan view of a ceiling fan simulating an aircraft engine, showing my new design;

FIG. 2 is a side elevational view thereof, the opposite side being a mirror image of that shown;

FIG. 3 is a top plan view thereof;

FIG. 4 is a partial cross-sectional view thereof, taken along the line 4—4 of FIG. 3, with the bottom portion rotated 45° and shown in side elevation and the fan blades omitted.

FIG. 1

FIG. 2

FIG. 3

FIG. 4
